UNITED STATES PATENT OFFICE

PASQUALE GALASSI, OF NEW YORK, N. Y.

INTERCHANGEABLE FLOOR STRIP

Application filed March 5, 1930. Serial No. 433,317.

This invention relates to improvements in dividing strips of the type employed in the construction of terrazzo and similar floors where the floor is divided into a number of 5 panels arranged according to a predetermined design.

Terrazzo, granolithic and similar floors generally comprise a lower or foundation bed made of concrete or cement or mortar or other 10 suitable material, and an upper or finishing layer generally consisting of a mixture of marble chips and cement, by means of which a good durable surface may be obtained as well as pleasing designs and color effects of a 15 practically unlimited variety.

The upper layer which is generally placed in position after the foundation layer has been allowed to harden to a sufficient degree of consistency, is generally divided into a 20 number of panels or units in a predetermined arrangement, which are obtained by outlining the desired design by means of dividing strips placed on or through the foundation layer.

25 The strips employed are generally made of relatively soft metal such as brass for instance, but are also at times made of different materials according to the ornamental requirements of the design and color scheme to be produced.

As a rule however, the metal employed is apt to be considerably more expensive than steel, and therefore it is desirable to substitute steel or some other inexpensive material 35 for the part of the strip which is embedded into the floor material and which is not likely to show even after the floor has been subjected to considerable wear.

In a patent entitled Dividing strip, granted 40 to me May 28, 1929, #1,715,193, I have described and claimed a strip composed of two sections interlocking with each other by means of male and female joints formed by their inner edge portions. Furthermore, in 45 a copending application entitled Terrazzo floor strips, Ser. No. 376,809, I have described and claimed a somewhat similar strip in which the joint portions of the strip extend laterally at one side thereof, this construction 50 tending to increase the rigidity of the struc-

ture and doing away with the necessity of providing additional anchoring and positioning means.

I have found that a more rigid joint between the two sections of a bimetallic strip 55 is obtained if the inner portion of the locking section is formed so as to have parts abutting against both sides of the inner portion of the other section.

I have also found that it is possible by the 60 construction herein advocated to obtain extremely rigid structures even when a strip of relatively light gauge is used for the lower or supporting section; furthermore, I have also found that it is possible to standardize 65 the construction of the lower or supporting section, while producing completed structures in which the upper portion may be of various thicknesses or may be made of different metals according to requirements. 70

The present invention is partly a division and partly a continuation of a pending application entitled Compound floor strips, Ser. No. 426,882, and its primary object is to provide a dividing strip for terrazzo and 75 like floors, of a rigid and relatively inexpensive construction, said strip being formed out of two sections the lower one of which may be standardized to interlock with upper sections of varying width or character. 80

Another object is to provide a bimetallic floor strip of relatively simple and strong construction entailing for its production a minimum quantity of metal, the two sections composing said strip being securely joined 85 to each other by operations requiring a relatively small expenditure of labor.

A still further object is to provide in a floor strip of the character specified a novel 90 and improved method of joining two strip sections together, said method insuring a maximum of rigidity and strength while entailing a comparatively small expenditure of labor. 95

A still further object is to provide a novel method of producing floor strips having upper sections of varying character and width, whereby by the standardization of certain parts of said strips it becomes possi- 100

ble to reduce to a minimum the investment required by tools and other production equipment.

Other objects and advantages of the present invention will more fully appear as the description proceeds and will be set forth and claimed in the appended claims.

My invention is illustrated by way of example in the accompanying drawings, in which:

Fig. 1 is a fragmentary view in perspective of a strip embodying my invention in which the means for locking in position the upper section are obtained by notching the upper edge of the lower section;

Fig. 2 is a vertical section thereof;

Fig. 3 is a fragmentary view in perspective of a somewhat similar strip in which the locking means are obtained by punching off portions of the body of the lower section without interfering with either one of its edges;

Fig. 4 is a vertical section thereof;

Figs. 5, 6, 7, 8 are vertical sections of similar strips in which a standardized lower section such as shown in Figs. 3 and 4 is used in connection with upper sections of varying character and width;

Fig. 9 is a fragmentary vertical cross section of a terrazzo floor showing the dividing strip of the type shown in Fig. 4 in position; and

Fig. 10 is a fragmentary vertical section of a terrazzo floor showing a dividing strip of the type shown in Fig. 6 in position.

The strip illustrated in Figs. 1, 2, comprises an upper section 11 and a lower section 12 interlocking therewith. The upper section consists of an angle bar having a vertical rib portion 13 and a laterally extending base flange 14. The lower section comprises a flat strip which may have an uninterrupted lower edge or else a lower edge notched at intervals as shown at 15 to produce longitudinally spaced lugs 16, the upper edge of said strip being slit at intervals to isolate tongue portions which may be bent to extend laterally of the body of the strip to form lugs or ears 17 collectively forming a longitudinal support for the base flange 14 of the upper section.

Lugs or ears 17 have their outer edges turned upwardly at a point laterally displaced from the inner surface of the body of the strip a distance corresponding to the width of the flange 14 so that the lower portion of the upper section can be placed directly between the upper edge portion of the lower section and the inner surface of the upturned edges of lugs or ears 17 as shown.

The upturned portion 18 of ears or lugs 17 extends beyond the upper edge of flange 14, so that the edge of said upturned portion 18 can be turned inwardly over the outer

edge of flange 14 as shown securely locking the upper section in position.

It will be observed that by virtue of this arrangement, the lower portion of the upper section remains imprisoned between the upper edge portion of the lower section and the lugs or ears extending laterally of said lower section, the result being a strip requiring comparatively few and simple operations for its manufacture yet having great rigidity and strength provided by the flange portion 14 of the upper section.

It is also possible to provide the equivalent of lugs or ears 17 without materially weakening the lower section by slitting its upper edge. This can be obtained by punching the strip at spaced intervals to isolate tongues from the body of the strip bending said tongues laterally so as to produce hook formed supporting and retaining members for the upper section.

Such a construction is illustrated in Figs. 3, 4, where 19 designates the upper section which is also in this case in the nature of an angle bar comprising a laterally extending base flange 20, and 21 designates the lower section punched at intervals to form openings at 22 isolating tongues which are bent laterally of the upper edge of said openings to form ears or lugs 23. Like in the previous case the outer edge portion of said ears or lugs 23 is bent upwardly as shown at 24 so as to form with the upper edge of the lower section a channeled ledge support for the base flange of the upper section. The upper edge of said upturned portion 24 is then bent inwardly over flange 20 as shown at 25 securely locking the upper section in position.

It is obvious that the construction of the lower section can be standardized so as to be useful in connection with upper sections of various widths and descriptions.

This possibility is clearly illustrated in Figs. 5, 6, 7, 8, in each one of which the same lower section is used in connection with a different upper section.

In Fig. 5 the upper section comprises a relatively thick upper portion 26 formed integral with a base portion 27 having an angle section having the same dimensions as the base portion of upper section 19 in Figs. 3 and 4 interlocking with and retained by the lower section. In a similar manner the upper section of the strip shown in Fig. 6 comprises a still thicker upper portion 28 and a base portion 29 which also has dimensions corresponding to those of the base portion of upper section 19 interlocking with the lower section.

The upper section illustrated in Fig. 7 consists of a U shaped shell portion 30 formed integral with an angle shaped base portion 31 the dimensions of which correspond to those of angle portions 27, 29, so as to also in

this case fit the standardized lower section 21. The chamber formed by the U shaped shell is filled with a suitable filler 32 which may be of metal different from that out of which the 5 shell is made or else may be a material possessing anti-slip properties such as lead or cement aggregate or rubber, etc.

A somewhat similar construction is shown in Fig. 8 where the upper section consists of 10 an open top shell 33 having a dovetailed section, said shell being formed integral with a base angle portion 34 depending therefrom said base portion being adapted to interlock with the lower section 21 as explained.

15 The chamber formed by shell 33 is also in this case filled by a suitable filler 35, said filler being securely retained in position by the inwardly inclined sides of the shell.

The use of a strip of the type shown in 20 Figs. 3, 4 is illustrated in Fig. 9 where 36 is a floor foundation, 37 is the lower layer of a terrazzo floor and 38 is the upper layer. In the same it will be observed that the lower 25 surface of lugs or ears 23 rests upon the top surface of the lower layer of the floor thus determining the depth at which the strip is to be inserted within the plastic material out of which the lower layer is made.

The remaining portion of the strip upwardly projecting from said lower layer therefore determines the depth of the lower layer, the strip being also anchored in position by the lateral projections formed by flange 20 and by lugs or ears 23.

35 In Fig. 10 I illustrate a floor in which a strip of the type shown in Fig. 6 is used, so as to demonstrate the various effects which can be obtained by the construction advocated. In said figure 39 is the foundation bed, 40 40 is the lower layer of the floor and 41 is the upper layer, the lower surface of the laterally extending lugs or ears being also in this case used to determine the depth at which the strip is to be inserted through the lower layer.

45 Although in all the drawings I show upper sections having angle shaped lower portions it is, of course, possible to use lower portions having different outlines, the idea being to produce upper sections having a standard 50 base portion adapted to interlock with a lower section of standardized construction said lower section being adapted to abut against both sides of and to interlock with said base portion. In practice however, I prefer to 55 use an upper section in the form of an angle bar because such a section can be easily produced out of a flat strip by bending its lower edge portion along a longitudinal line so as to form a laterally extending flange when 60 relatively thin upper sections are used. It is obvious that although in every case I have shown the laterally extending flange bent at 90 degrees to the vertical body of the upper section, it is possible to incline said flange 65 at a greater or lesser angle if desired.

The constructional details of my improved strip may further vary from those shown without departing from the inventive idea; the drawings will therefore be understood as being intended for illustrative purposes only and not in a limiting sense. 70

Accordingly, I reserve the right to carry my invention into practice in all those ways and manners which may enter, fairly, into the scope of the appended claims. 75

I claim:

1. A dividing strip for terrazzo and like floors, comprising upper and lower longitudinal sections, one of said sections having its inner edge formed with a laterally extending portion, the inner edge portion of the other section abutting against the surface of the other section opposite that from which said laterally extending portion extends, said other section having laterally extending lugs struck off the body thereof, embracing said laterally extending portion. 80

2. A dividing strip for terrazzo and like floors, comprising upper and lower longitudinal sections, said upper section having 90 its inner edge formed with a laterally extending portion, the inner edge portion of said lower section abutting against the surface of said upper section opposite that from which said laterally extending portion extends, said lower section having laterally extending lugs struck off the body thereof, supporting and retaining said laterally extending portion. 95

3. A dividing strip for terrazzo and like floors, comprising upper and lower longitudinal sections, said upper section having its inner edge formed with a laterally extending flange, the inner edge portion of said lower section abutting against the surface 105 of said upper section opposite that from which said laterally extending flange extends, said lower section having laterally extending lugs struck off the body thereof, supporting and retaining said laterally extending flange. 110

4. A dividing strip for terrazzo and like floors, comprising upper and lower longitudinal sections, said upper section having an angle shaped inner edge portion having 115 a laterally extending flange, the inner edge of said lower section abutting against the surface of said angle shaped portion opposite that from which said flange extends, said lower section having laterally extending lugs struck off the body thereof, supporting and retaining said laterally extending flange. 120

5. A dividing strip for terrazzo and like floors, comprising upper and lower longitudinal sections, said upper section having an angle shaped inner edge portion having a laterally extending flange, the inner edge of said lower section abutting against the surface of said angle shaped portion opposite that from which said flange extends, said 125 130

lower section having laterally extending lugs struck off the body thereof, supporting said laterally extending flange, the outer edges of said lugs being bent over the edge of said flange so as to securely lock said sections to each other.

6. The method of joining to each other an angle section and a flat sheet metal section, which consists in offsetting portions of the 10 body of said flat section to form lugs extending laterally thereof, at an angle substantially corresponding to that of the angle section, nesting the corner portion of said angle section within and against the side surface 15 of said flat section and the surfaces of said lugs, and folding the outer ends of said lugs over the edge of the flange of said angle section abutting thereagainst.

7. A dividing strip for terrazzo and like 20 floors, comprising upper and lower longitudinal sections, one of said sections having its inner edge formed with a laterally extending portion, the other section having lugs laterally extending therefrom at longitudinally spaced intervals along a line spaced 25 from its inner edge, the inner edge portion of said first mentioned section abutting against the side of the inner edge portion of the second mentioned section, said laterally extending portion abutting against said lugs, said lugs embracing and retaining the outer edge of said laterally extending portion.

8. A dividing strip for terrazzo and like 30 floors, comprising upper and lower longitudinal sections, one of said sections having its inner edge formed with a laterally extending flange, the other section having lugs laterally extending therefrom at longitudinally spaced intervals along a line spaced 35 from its inner edge, the inner edge portion of said first mentioned section abutting against the side of the inner edge portion of the second mentioned section, said laterally 40 extending flange abutting against said lugs, said lugs embracing and retaining the outer edge of said laterally extending portion.

9. A dividing strip for terrazzo and like 45 floors, comprising upper and lower longitudinal sections, one of said sections having its inner edge formed with a laterally extending portion, and the other section having lugs laterally extending therefrom at longitudinally spaced intervals along a line spaced 50 from its inner edge, the inner edge portion of said first mentioned section abutting against the side of the inner edge portion of the second mentioned section, said laterally 55 extending portion abutting against said lugs, said lugs embracing and retaining the outer edge of said laterally extending portion, so as to connect said sections to each other, the resulting laterally extending connection being adapted to act as positioning and anchoring 60 means for said strip.

10. A dividing strip for terrazzo and like floors, comprising upper and lower longitudinal sections, said upper section having its inner edge formed with a laterally extending portion, said lower section having parts extending laterally and upwardly thereof, forming a U-section with its inner edge portion, the inner edge of said upper section and the portion laterally extending therefrom being inserted within said U- 70 section and being supported and retained thereby.

11. A dividing strip for terrazzo and like floors, comprising upper and lower longitudinal sections, said upper section having its inner edge formed with a laterally extending flange, said lower section having parts extending laterally and upwardly thereof, forming a U-section with its inner edge portion, the inner edge of said upper section 80 and the flange laterally extending therefrom being inserted within said U-section and being supported and retained thereby.
